Patented Dec. 9, 1924.

UNITED STATES PATENT OFFICE.

FUMI MORINAGA, OF NEW YORK, N. Y.

DESIGN FOR AN AERIAL TOY.

Application filed September 11, 1923. Serial No. 7,181. Term of patent 14 years.

To all whom it may concern:

Be it known that I, FUMI MORINAGA, a citizen of Japan, residing at New York city, borough of Manhattan, in the county of New York and State of New York, have invented a new, original, and ornamental Design for Aerial Toys, of which the following is a specification, reference being

had to the accompanying drawing, forming part thereof.

The figure is a perspective view of an aerial toy, showing my new design.

I claim:

The ornamental design for an aerial toy, as shown.

FUMI MORINAGA.
